*E. Reynolds,
Bending Wood,
Patented July 17, 1835.*

Granted for Seven years from 1st July 1835
Edward Reynolds of Huddersfield New Jersey. 8972 X
7/17/1835

Litters Patent

The machine referred to in this Litter Patent and making part of the same containing a description in the words of the late Edward Reynolds himself of his improvement in a machine for bending or setting felloes for the wheels of carriages and waggons.

To all whom it may concern:

Be it known that I Edward Reynolds of Huddersfield in the County of Manchester, and State of New Jersey, have invented a new and useful machine for bending or setting felloes for the wheels of carriages and waggons of all descriptions and that the following is a full and exact description thereof.

The felloes are to be dimensioned, or nearly so, its being intended generally that two or them should form the rim of a wheel. The timber either sawed or run, is to be bent round cylinders, which cylinders may be somewhat less in diameter than one fourth or one fifth, than that of the interior of the wheel. The bending machine is furnished with two such cylinders, one of them intended for the larger and the other for the smaller size wheels. These I make of wood of such thickness that for the lighter kind of wheels three may be bent thereon, side by side, at the same time. These cylinders are placed horizontally upon a stout bench immovably fixed, each of the cylinders revolves on a strong bolt forming its axis. One of these bolts is permanent fixed in the bench, the other passes at each end through a slot or mortise in the bench, and in a piece of timber placed above the cylinder to receive them. This is for the purpose of regulating the distance of the cylinders from each other, which should in all cases be equal to that of the thickness of the timber to be bent. A regulating screw is made to operate upon each end of the sliding bolt, or rather against a sliding block, which receives the bolt. It will be found convenient to remove a part of each of the cylinders, say one fourth from the larger and one sixth from the smaller by cutting them in circumference, by a vertical section in a straight line, a sufficient portion of the cylinder being still left to effect the setting or bending. A hole or mortise in the middle of the part left of each cylinder to receive a bar spike by which to apply the regulation screw. When well dressed up the mortise should be made in the edge of the

expander. At one of the ends formed by the flanges and curved part of each cylinder a small hole is to be formed to receive a wire and confine one of the ends of the stuff whilst the flanges are to be formed and holes are bored at suitable distances around the edges of the cylinders, to receive the bolt of a movable or shifting clevis which is used to confine the other end of the stuff after it has been set. The edges of the clevis should be graduated or marked off in feet and inches, in order to determine with facility the exact place at which they must stand when the process of bending is commenced to cause the angle on the cylinder to come one or two inches short of the end of the flange (when bent in order to afford sufficient room for the forming of the shifting clevis. When the machine is to be used, the stuff to be bent is prepared by baling or steaming in the usual manner. One of the ends is then placed under the stationary clevis together with a piece of iron of proper length and width which, as the stuff is bent, laps around its outer edge and prevents the formation of chocks and splinters. The other end of the iron strap is sometimes made to terminate in a screw furnished with a nut, which may be passed through an iron plate on the edge of the cylinder, the strap may then be drawn firmly around the flanges, as shown in the model and drawing deposited in the Patent office.

What I claim as my invention and for which I ask a Patent is the machine or apparatus as herein described, and may be properly be denominated revolving cylinder, to be used for the bending of billets, for carriages and wagons of all descriptions, stings, runners, iron tires for wheels, loops, sets, hoops, vessels, mast hoops, &c. In which machine two cylinders are employed operating together by means of certain necessary parts in the manner as upon the principles herein set forth, not intended however to limit myself in the formation of the necessary parts or to the specific herein stated, but to vary them in any way and to apply them to any use not varying from the principle as I may find convenient whilst the machine continues substantially the same and a similar effect is produced by analogous means.

Witness,
